(57) CLAIM

The ornamental design for a bolt carrier, as shown and described.

DESCRIPTION

FIG. 1 is a perspective view showing our new design for a bolt carrier,
FIG. 2 is a right side view thereof,
FIG. 3 is a left side view thereof,
FIG. 4 is a top view thereof,
FIG. 5 is a bottom view thereof,
FIG. 6 is a front view thereof,
FIG. 7 is a rear view thereof; and,
FIG. 8 is an exploded view illustrating the bolt carrier of the present invention in its environment of use. The dotted lines are for illustrative purposes only, forming no part of the claimed design.
